UNITED STATES PATENT OFFICE

TREFFON SIAMPOS, OF EDWARDSVILLE, ILLINOIS

CIGARETTE

Application filed July 16, 1931. Serial No. 551,221.

This invention relates to cigarettes and has for its object the production of a simple and efficient means for producing a cigarette which will not become moist at the end 5 thereof when placed in the mouth.

One of the most important objects of the present invention is the production of a simple and efficient tip for cigarettes which may be either molded or slipped over the end of 10 the cigarette, and which may be made of light transparent, or any suitable or convenient material.

Other objects of the invention will appear throughout the following specification and 15 claim.

In the drawing:

Figure 1 is a perspective view of the cigarette showing the tip attached thereto;

Figure 2 is a side elevation of the cigarette 20 showing the tip in section;

Figure 3 is an end view of the tip;

Figure 4 is a view looking at the interior of the tip, showing a modified form thereof;

Figure 5 is a longitudinal sectional view 25 through the form of the tip shown in Figure 4; and

Figure 6 is a section taken on line 6—6 of Figure 4.

By referring to the drawing, it will be seen 30 that 1 designates the cigarette which is provided with a tip 2, which tip may be formed upon the cigarette by molding or dipping the cigarette into plastic or moldable material and after the end of the cigarette has been 35 dipped, a suitable aperture or vent 3 may be formed by punching or perforating the end of the cigarette tip by means of a needle or other suitable instrument. This tip may be formed of light transparent, or in fact, any 40 suitable or convenient or desirable gelatinous material which may be formed readily by dipping the end of the cigarette into the liquid material which will then harden around the end of the cigarette.

The structure shown in Figure 2 illustrates 45 a tip 4 which is preferably molded and then slipped over the cigarette and this tip may be formed in any suitable or desired shape without departing from the spirit of the invention. The tip 4 preferably comprises an

elongated thimble-like structure having a closed end 5 which is provided with a vent opening 6 in the center thereof to permit the smoker to draw the smoke from the cigarette 55 while smoking.

It should be understood that any suitable or desired number of apertures may be formed in the end of the tip 4 without departing from the spirit of the invention and the design or shape of the tip may be varied 60 also without departing from the spirit of the invention.

In Figures 4, 5 and 6, I have shown a modified form of the invention wherein a tip 7 is employed of an elongated thimble-like 65 body having a substantially closed end wall 8, and an outer end 9, into which outer end 9 the cigarette 10 is adapted to be placed. The end wall 8 is provided with a centrally located aperture 11 and upon the inner face 70 of the end wall 8 are provided radially extending or radiating grooves or channels 12 all leading to the centrally located aperture 11. These channels 12 will direct all of the 75 smoke from the end of the cigarette 10 down to the centrally located aperture 11 and facilitate the smoking of a cigarette. It should be understood that the tip 7 is preferably formed of material sufficiently sturdy 80 to prevent the deterioration thereof by contact with the lips of the smoker, and also prevent the moistening of the end of the cigarette while the cigarette is being smoked. It is not desired, however, to limit the particular material from which the device may 85 be made in this particular application.

It should be further understood that certain detail changes in the mechanical construction may be employed without departing from the spirit of the invention. 90

Having described the invention, what is claimed as new is:

As a new article of manufacture, a tip for attachment to a cigarette comprising a thin thimble-like structure having a hollow body 95 and an end wall, said end wall provided with a draft aperture formed therein, the inner face of said end wall being provided with radiating channels communicating with and extending from said aperture toward the side 100

walls of said tip for conveying smoke from the side walls of the tip toward said central aperture and permitting a draft to be created over a maximum area of the inner end of a cigarette adapted to be inserted in said tip.

In testimony whereof I affix my signature.
